(57) **CLAIM**

The ornamental design for an insert trim for garage door windows, as shown and described.

DESCRIPTION

FIG. 1 is a front, perspective view of the insert trim for garage door windows of the invention;

FIG. 2 is a right side view of the insert trim for garage door windows of FIG. 1;

FIG. 3 is a bottom view of the insert trim for garage door windows of FIG. 1;

FIG. 4 is a back, perspective view of the insert trim for garage door windows of the invention;

FIG. 5 is a left side view of the insert trim for garage door windows of FIG. 4;

FIG. 6 is a top view of the insert trim for garage door windows of FIG. 4;

FIG. 7 is a cross sectional view taken along lines VII—VII in FIG. 1; and,

FIG. 8 is a perspective view of a structure with the garage door of the invention in place, the door and associated structures in broken lines not forming a part of the invention.
